CHASER AND CHASER CLAMP

Charles A. Reimschissel, Waynesboro, Pa., assignor to Landis Machine Company, Waynesboro, Pa., a corporation of Pennsylvania

REISSUED

Application December 7, 1933, Serial No. 701,366

9 Claims. (Cl. 10—104)

This invention relates to thread cutting chasers and holders and particularly to chasers of the tangential type. The object of the invention is to provide an improved tangential chaser and further to provide improved means for adjusting and locating the chaser in correct cutting position and for clamping it in a die head.

Further objects and advantages will become apparent from the description which follows.

10 Referring to the accompanying drawing, which is made a part hereof and on which similar reference characters indicate similar parts,

Figure 1 is a somewhat diagrammatic view illustrating the positions of chasers when in cutting relation with the work,

Figure 2, an end view of one form of chaser showing grooves for adjusting the chaser and securing it against longitudinal movement,

Figure 3, a view of a chaser showing a different 20 form of groove,

Figures 4 and 5 are plan views of the chasers shown in Figures 2 and 3, respectively,

Figure 6 is an end view of a clamp having grooves corresponding to those shown in Figures 25 3 and 5,

Figure 7 is a plan view of the under side of the clamp shown in Figure 6,

Figure 8 is an end view of a chaser and clamp positioned in a holder on a threading head,

30 Figure 9, a plan view of the chaser clamp and holder, shown in Figure 8,

Figure 10, a face view looking from the right of the arrangement shown in Figure 9, and

35 Figure 11, a fragmentary sectional view showing the cooperating grooves on the clamp and chaser.

In the drawing numeral 10 indicates a thread cutting chaser of the tangential type having thread cutting serrations on its face, a throat or starting bevel 38, a beveled base 11, a beveled top 12 with parallel grooves 13 on the beveled top (Figs. 2, 4). In Figures 3 and 5 the chaser 14 has a beveled base 15, cutting serrations on its face and a beveled top 16 and grooves 17, the bottoms of which grooves are at an angle to the tops of the grooves. The form of the chaser shown in Figures 3 and 5 is that shown in the combinations of the remaining figures in the drawing. A chaser clamp 18 has a beveled portion 19 adapted to seat on a corresponding beveled portion 20 on the holder block 21. The holder block may be any form of holder, that shown being a sliding holder mounted in an opening in a threading head. The clamp has beveled

grooves 22 adapted to engage the grooves 17 in the top of the chaser 14. The grooves shown are the beveled kind but may be parallel grooves adapted to cooperate with the parallel grooves 13 of the chaser 10. The clamp is also provided with elongated holes 23 through which extend securing bolts 24, the bolts engaging in threaded holes in the block 21. The block 21 also is provided with a lug 25 through which an adjusting screw 26 is threaded to engage the end of the 10 clamp for adjusting the clamp and for holding it in adjusted position. The block 21 has a seat 27 and a face portion 28 against which seat and face portion the beveled base 15 and back of the chaser rest when the chaser is held in operative position. At 29 is shown a setting gauge having an adjustable screw 30 for locating the cutting tips of the chaser. The screw 30 is held in adjustable position by means of screw 31.

When either the chaser 10 or 14 is placed in 20 the holder 21 the beveled base of the chaser and the back seat respectively against surfaces 27 and 28 in the block. The clamp 18 is secured in position by means of the screws 24. The grooves 22 of the clamp engage in the grooves 17 of the 25 chaser and hold the chaser against endwise movement. A slight adjustment of the chaser for correct position may be made by adjusting screw 26. The elongated slots 23 in the clamp provide sufficient end movement so that in grinding the chasers it is not necessary to grind off any definite amount of the cutting edge in sharpening the chasers. The slots 23 permit sufficient relative movement between the clamp and the holder to allow the chaser to be moved longitudinally in 30 relation to the holder the pitch or distance apart of the grooves 17.

The relation of the cutting edge of the chasers to the center of rotation of the work when cutting thread is determined somewhat by the structure of the metal being threaded. The setting gauge 29 is provided whereby the chasers may be uniformly set in the holders in relation to the center of rotation of the work. The chasers are clamped in fixed operative position by the clamps 40 18. The grooves 22 engage over the ridges 34 on the chaser. The force of the clamping action is directed against the chaser on the surface 16 and on the root surface 35, however, it is not limited to this surface but can be altered so that 50 the clamping force may be directed against root surfaces 32 (Fig. 11) and crest surface 33 or by inclining the sides of the grooves similar to the Acme form of thread, the clamping force can be directed against the side angles of the grooves. 55

The construction illustrated permits accurate clamping of the chaser, prevents the chaser from changing its correct cutting position in relation to the holder 21 and provides means for adjusting the chaser to the proper cutting position.

It will be obvious to those skilled in the art that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

1. In a threading die head, a holder block having a recess for a chaser, a chaser mounted in said recess, said chaser having thread cutting serrations on its face and having its top provided with a plurality of parallel grooves, a clamp mounted on and secured to said block, said clamp being arranged to clamp the chaser to said block and having grooves adapted to co-operate with the grooves of the chaser, and means for adjusting the clamp and chaser longitudinally of their axes in the block to position said chaser in thread cutting position.

2. In a threading die head, a holder block having a recess for a chaser and a recess for a clamp, a chaser mounted in said first named recess and a clamp mounted in said last named recess, means for holding said clamp in its recess, the chaser having a beveled base, thread cutting serrations on its face, a beveled top and a plurality of grooves cut in its top extending from the face to the back of said chaser and the clamp having a plurality of corresponding ridges adapted to engage the grooves of the chaser, and adjustable means for abutting the clamp to adjust it and secure it against end thrust during a threading operation.

3. In a threading die head, a holder block having a recess, a chaser slidably mounted in said recess, said chaser having a plurality of grooves cut in its top, a substantially U-shaped clamp member having a beveled surface at the end of one leg adapted to slide upon a corresponding surface formed upon said block and having a plurality of grooves on the end of the other leg adapted to mate with the grooves on the top of said chaser to hold the chaser and clamp against relative movement and means engaging said clamp

member for adjusting the member and chaser in unison when desired.

4. A threading die head of the type set forth in claim 3, wherein the mating grooves are beveled oppositely.

5. A threading die head comprising a holder block having a recess, a chaser slidably mounted in said recess, said chaser having a plurality of grooves cut in its top, said holder block having a second recess, a substantially U-shaped clamp 10 mounted in said recess comprising a beveled surface on the end of one leg for slidably engaging a corresponding surface in said recess and a grooved surface on the end of said other leg for engaging and mating with the grooves in said 15 chaser, means for fastening said clamp to said holder for limited movement relative thereto and means for moving said clamp and chaser longitudinally in unison to position the chaser in the holder block.

20 6. A die head as set forth in claim 5 wherein the means for moving comprises a screw threaded through said block and engaging an end of said clamp.

7. In a threading die head, a chaser having a 25 beveled base, a beveled top, thread cutting serrations on its face and a plurality of grooves extending from the face to the back of said chaser; a grooved clamp for clamping said chaser engaging said plurality of grooves; and means for 30 adjusting said chaser and said clamp to set said chaser to correct cutting position in the head independent of the relation of the cutting edge to said grooves on said chaser.

8. A chaser having a face provided with thread 35 cutting serrations, a beveled base portion, and a beveled top portion, one of said portions being provided with parallel grooves extending from the face to the back of said chaser, the bottoms of said grooves being at an angle to said one of the bevelled portions.

9. For use with a chaser holder in which a clamp is drawn in a direction substantially parallel to the cutting serrations, a tangential chaser having one face provided with thread cutting 45 serrations, a throat or starting bevel adjoining said serrations, a beveled base portion, a beveled top portion adjoining said starting bevel, said beveled top being provided with parallel grooves extending from said starting bevel to the back 50 of the chaser.

CHARLES A. REIMSCHISSEL.
